(57) **CLAIM**

The ornamental design for a tooth for hand tools, as shown.

DESCRIPTION

FIG. 1 is a perspective view of a tooth for hand tools showing my new design;

FIG. 2 is a front view thereof, the rear view being a mirror image thereof;

FIG. 3 is a top view thereof, the bottom view being a mirror image thereof;

FIG. 4 is a sectional view thereof taken along the lines A-A in FIG. 3;

FIG. 5 is a sectional view thereof taken along the lines B-B in FIG. 3;

FIG. 6 is a perspective view of a tooth for hand tools showing a second embodiment of my new design; and,

FIG. 7 is a second perspective view of a tooth for hand tools of my design shown in FIGS. 1-5.

A rear side view is symmetry to the front side view, and a bottom view is symmetry to the top view, thus the rear side view and the bottom view are omitted.

The broken lines depict portions of the tooth for hand tools that form no part of the claimed design.
